UNITED STATES PATENT OFFICE.

GEORGE CARL VOSS, OF EXIRA, IOWA.

BROOD-FRAME HOLDER.

Application filed March 13, 1922. Serial No. 543,242.

To all whom it may concern:

Be it known that I, GEORGE C. Voss, a citizen of the United States, and a resident of Exira, in the county of Audubon and 5 State of Iowa, have invented a certain new and useful Brood-Frame Holder, of which the following is a specification.

The object of my invention is to provide a brood frame holder adapted to be used in 10 connection with the bee industry, the parts of my device being of simple, durable, and comparatively inexpensive construction.

More particularly my invention relates to 15 a holder device wherein brood frames may be held in position for assembling purposes.

Still a further object is to provide such a device wherein the parts are capable of being moved to various positions and locked in any of their various positions when as 20 sembling the brood frames.

With these and other objects in view, my 25 invention consists in the construction, arrangement and combination of the various parts of my device, whereby the objects contemplated are attained, as hereinafter more fully set forth, pointed out in my claims, and illustrated in the accompanying drawings, in which:

Figure 1 is a front elevation of my im 30 proved device with a brood frame shown thereon.

Figure 2 is a side elevation of the same.

Figure 3 is a front elevation of a portion 35 of the holder device, the brood frame being held, as shown, under tension.

Figure 4 is a front elevation of the holder frame.

Figure 5 is a detailed, sectional view taken on line 5—5 of Figure 1.

Figure 6 is a sectional view taken on line 40 6—6 of Figure 2, showing a brake structure; and

Figure 7 is an end view of the honey containing frame or brood frame.

In the accompanying drawings, I have 45 used the reference numeral 10 to indicate generally a supporting frame which is provided with a base 11 and a reinforcing bar 12. Mounted on the supporting frame 10 is the holder member A.

The holder member A consists of a plate 13 having a hub 14 formed on its rear side, which rests against the supporting frame 10. The plate 13 is mounted on the bolt 15 which

is extended through an opening formed in 55 the support 10.

From the construction of the parts just described it will be seen that the holder member A is capable of rotation relative to the support 10. 60

On one of the ends of the plate 13 are formed a pair of ears 16 and 17, while on the opposite end of the plate 13 is formed the ear 18. On each of the ears 16, 17, and 18 is mounted a spool 19. Extended through 65 the spool 19 and forming an axis therefor is a screw or the like 20. The purpose of the parts just described will be hereinafter more fully set forth.

In order to lock the holder member A 70 against rotation, I provide a brake structure which includes a foot lever 21 pivoted on the support 10 by means of the bolt 22.

Secured to a hook bolt 23 on the lever 21 75 is a band of resilient material 24. The band 24 extends around the hub member 14 and has its free end fixed to the support 10 by means of the bolt 25.

From the construction of the parts just described, it will be seen that the pressure 80 applied on the foot lever 21 will cause the band 24 to frictionally engage the hub 14 and prevent the rotation of the holder member A.

Fixed on the lower edge of the plate 13 is 85 a strip or cleat 26, having a projecting portion 27, resting upon the lower edge of the plate 13. Mounted on the plate 13 is another plate 28. The plate 28 has its lower edges spaced from the cleat 26 as clearly illustrated 90 in the drawings. The upper edge of the plate 28 is curved from end to end as at 29.

The spacing of the plate 28 from the cleat 26 forms a groove 30, the purpose of which will be hereinafter more fully set 95 forth.

Spaced from the upper edge of the plate 28 and fixed to the plate 13 are a pair of cleats 31. The cleats 31 and the upper edge of the plate 28 are spaced from each other 100 so as to provide a guide way 32. The cleats project out beyond the edges of the plate 28 and are provided with downturned flanges 31^a. The flanges 31^a will prevent any end-wise movement of the frames when they are 105 being assembled.

The frames, which are designed to be assembled upon the device just described are

sometimes called honey containing frames or brood frames, and consist of a pair of end bars 33, a bottom bar 34, and top bar 35.

Each of the ends of the end bars 33 are bifurcated so as to receive tongues 36 which are formed on the ends of the bars 34 and 35.

I will now describe the use of my device when the brood frames are being assembled. The bottom bar 34 is placed within the groove 30. Its ends being projected out slightly beyond the ends of the plate 13. The two end bars 33 are then placed against the ends of the plate 13 so that the bifurcated portion thereof is received upon the tongues 36, on the bottom bar 34.

The top bar 35 is then placed within the guide way 32 with its tongues 36 being received in the bifurcated portion of the end bars 33.

20 The tongues 36 on the top bar 35 project out beyond the end bars 33 so that they may be supported within the supers of the bee hives.

In order to hold the parts together even 25 though they are not nailed, I provide a cam lever 37. The cam lever 37 is mounted on the bolt 38.

When the brood frames are placed upon the holder A, they are first in the position 30 shown in Figure 1 of the drawings, and when the cam lever is moved to the position shown in Figure 2 of the drawings it will cause the bottom bar 34 and the upper bar 35 to be bowed.

35 The projection 27 on the cleat 26 will hold the center of the bottom bar 34 against movement while its ends will be bowed downward. The cam lever 37 will cause the upper bar 35 to conform to the contour 40 of the upper edge of the plate 28. The end pieces 33 prevent any movement of the bars 34 and 35 near their ends.

45 While the parts are under tension it is very easy to drive nails through the tongues 36 of the upper bar 35 into the end pieces 33.

50 The releasing of pressure upon the foot lever 21 will then permit the entire holder means and brood frame to be rotated for bringing the bottom bar 34 to position where it will be easy to drive nails through it into the end bars 33.

It will be seen that the entire holder member may be swung into various positions 55 and locked in any position, by the operator simply pressing his foot on the lever 21.

On the support 10, I mount a box 39 having a number of partitions thereon for receiving various sizes of nails.

60 Some of the brood frames are "wired." The frames are ordinarily "wired" when they are used for a foundation frame.

The end bars 33 are provided with a number of small openings 40 for permitting the 65 wires 41 to be extended therethrough.

On the upper end of the support 10, I place bars or brackets 42 which forms a bearing for the rod 43. The rod 43 is provided with a crank portion 44 which serves as a handle.

70 Rotatably mounted on the rod 43 and between the brackets 42 is a spool 45, having the wire 41 thereon. A guide element 46 is provided on the support 10 through which the wire 41 is extended. A flat spring 47 is fixed to the upper end of the support 10 and engages the spool 45 for preventing its undesired rotation and for holding it under a slight tension. The wire holding device may be placed on the side of the support 10 80 or upon any suitable bracket in such manner that it will be easily accessible.

When the wire is extended through the end bars 33, it is projected in through one of the openings and threaded through an 85 opening in the other end bar. The wire then passes around one of the spool members 19 and is threaded back through both of the bars 33 and again around the spool 19, and so on.

90 The passing of the wire around the spool 19 will permit the wire to be easily drawn through the various openings in the end bars 33 without the effect of any binding. After the wire is threaded into the end bars 95 of the frame, it is then slipped off the spools 19 and drawn tight. The ends of the wire are then fastened to the end bars 33.

The brood frame is then released by releasing the cam lever 37, and removed from 100 the holder A. The releasing of the cam lever 37 will permit the bottom bar 34 and the top bar 35 to spring back to normal position. This tends to pull the wire 41 taut between the end bars 33.

105 It will be seen that the frames may be quickly and easily assembled on my device.

The advantage of my structure is that it enables one to assemble the brood frames so that they will be absolutely true and that 110 each corner will form a true right angle.

It will be seen that whenever it is desired to wire the frames it can easily be accomplished by rotating the entire holder member A.

115 Some changes may be made in the construction and arrangement of the parts of my device without departing from the real spirit and purpose of my invention, and it is my intention to cover by my claims, any 120 modified forms of structure or use of mechanical equivalents, which may be reasonably included within their scope.

I claim as my invention:

1. In a device adapted to hold a rectangular frame consisting of a pair of end bars, a bottom bar and a top bar, for assembling purposes, including a support, a frame holder rotatably mounted on said support, a brake device for locking said frame holder in any 125 130

- of its positions, said frame holder having a groove designed to receive the bottom bar, a guide way formed on said holder for receiving the upper bar, means for locking said upper bar against movement, whereby the end bars may be positioned between the ends of the bottom and upper bars all for the purposes stated.
2. In a device adapted to hold a rectangular frame consisting of a pair of end bars, a bottom bar and a top bar for assembling purposes, including a support, a frame holder rotatably mounted on said support, a brake device for locking said frame holder in any of its positions, said frame holder having a groove designed to receive the bottom bar, a guide way formed on said holder for receiving the upper bar, said guide way having its lower edge curved from end to end, means for locking said upper bar against movement, whereby the end bars may be positioned between the ends of the bottom and upper bars all for the purposes stated.
3. In a device adapted to hold a rectangular frame consisting of a pair of end bars, a bottom bar and a top bar for assembling purposes including a support, a frame holder rotatably mounted on said support, a brake device for locking said frame holder in any of its positions, said frame holder having a groove designed to receive the bottom bar, a guide way formed on said holder for receiving the upper bar, said guide way having its lower edge curved from end to end, the ends of said upper and bottom bars being longer than the length of said holder whereby the end bars may be placed in between the projected ends of said upper and bottom bars, means for bowing said upper bar so that the end bars will be held under pressure between the upper and bottom bars as and for the purposes stated.
4. In a device adapted to hold a rectangular frame consisting of a pair of end bars, a bottom bar and a top bar for assembling purposes including a support, a frame holder rotatably mounted on said support, a brake device for locking said frame holder in any of its positions, said frame holder having a groove designed to receive the bottom bar, a projection formed on the bottom side of said groove designed to engage the bottom bar midway between its ends for permitting it to bow, a guide way formed on said holder for receiving the upper bar, said guide way having its lower edge curved from end to end, the ends of said upper and bottom bars being longer than the length of said holder whereby the end bars may be placed in between the projected ends of said upper and bottom bars, means for bowing said upper bar so that the end bars will be held under pressure between the upper and bottom bars as and for the purposes stated.

Des Moines, Iowa, February 28, 1922.

GEORGE CARL VOSS.
